UNITED STATES PATENT OFFICE.

LOUIS BALTER, OF NEW YORK, N. Y., ASSIGNOR TO BALTER TRAY MANUFACTURING CO., INC., OF NEW YORK, N. Y., A CORPORATION OF NEW YORK.

DENTAL TRAY.

Application filed January 18, 1923. Serial No. 613,323.

To all whom it may concern:

Be it known that I, LOUIS BALTER, a citizen of the United States, residing at New York city, in the county and State of New York, have invented certain new and useful Improvements in Dental Trays, fully described and represented in the following specification and the accompanying drawings, forming a part of the same.

10 This invention relates to improvements in dental trays.

It is the principal aim of the present invention to provide an improved tray for dental purposes, which shall be especially useful in taking plaster impressions for use in making upper and lower sets of artificial teeth. By the use of the present tray, various difficulties heretofore experienced will be overcome, some of which have been due 20 either to the presence of one or more teeth remaining in the jaw of which the impression is made, with consequent adherence of the plaster to such tooth or teeth, thus occasioning much pain to the patient in attempting to remove the plaster cast in as few parts as possible to facilitate its assembly for further use. In many instances, however, it is necessary to break the plaster cast to an objectionable extent, and, in numerous 30 instances, into so many parts that accurate re-assembly thereof is impossible, with the result that the whole operation has to be repeated. Even where no teeth are in the jaw of which a plaster impression is to be made, it frequently happens that there are 35 ridges on the gums, and this, of course, will occasion difficulty in removing the set plaster therefrom unless broken to an unfavorable extent with much discomfort to the 40 patient. Briefly, the present invention comprises a tray made up of a plurality of members hinged or pivotally secured together, and having means positioned in the trough of the tray for weakening or otherwise predisposing the plaster cast to breakage on a 45 predetermined line, which, in the best forms of the invention, will be on a line conforming generally to the curvature of the teeth or gums, so that the plaster cast may be removed, in many cases, in two parts, or at 50 least in such few parts as to make re-assembly of such parts possible with accuracy. Also, due to the hinged or pivoted tray sections being so formed as to enable 55 them to be forced apart readily on the line

of the teeth or gums or both, as hereinafter explained, so as to cause breakage of the set plaster on such predetermined line, and also because such breakage force is applied laterally to the teeth embedded in the plaster, or to the gums, it will be readily seen that the patient suffers no ill effects in the operation of taking an impression for either a whole or half plate, as heretofore.

60 In order that those skilled in the art may understand my invention, the best embodiments thereof will now be described in detail, in connection with the illustration thereof in the accompanying drawings, and the novel features of the invention then be 65 pointed out in the claims.

In the drawings—

Figs. 1 and 2 are, respectively, top and bottom plan views of a lower tray embodying my invention;

75 Fig. 3 is a section on the line 3—3 of Fig. 1;

Fig. 4 is a section of a tray taken on a similar line, but omitting the palatal arch, and showing, therefore, a lower tray in cross 80 section with the lingual opening therein;

Fig. 5 is a section on the line 5—5 of Fig. 6, and

Fig. 6 is a modified construction of tray.

Fig. 7 is a section on the line 7—7 of Fig. 1.

Referring now to the drawings, and especially Figs. 1—5, the reference letters A, B, designate, respectively, the two-part outer tray member and the inner tray member. The line of separation between the outer members and the inner tray member preferably conforms in shape approximately to that of a set of teeth. On the meeting edges of the tray members, that is, the inner edge of the outer members and the outer edge of the inner member, are formed upturned rims D, the arrangement being such that when the tray members are in assembled position such rims will meet and form a ridge conforming in shape to the meeting edges of the members, so that plaster which has set or hardened in the tray before removal from the patient's mouth, will be predisposed to breakage along the line of such ridge, and such breakage may be conveniently accomplished without pain or discomfort to the patient by inserting a flat instrument, such, for instance, as a knife blade, between the rims and prying them

apart, whereupon the plaster will, in almost every instance, break only along the line of the ridge and thus enable the cast to be readily re-assembled for further use in making the plate.

The outer tray members A are preferably pivoted to the handle portion E by a pivot F arranged to positively and rigidly hold the parts in assembled position when an impression is to be made, and also for keeping the tray parts together when not in use. The handle E and such pivot are also arranged to co-operate with an elongated wedge E', the latter being insertible in a dove-tailed groove H formed on the bottom of the inner tray member, the pivot F engaging a threaded hole in such elongated wedge when the parts are in assembled position.

20 The modification (Fig. 6) shows a tray for taking impressions where no back teeth are in the jaw, such tray having saddle portions L, or portions consisting only of the plaster holding trough, and the frontal section 25 only being provided with a ridge formed by the meeting edges or rims formed on such inner and outer sections, so that when an impression is to be taken where only the front teeth are present, it is only necessary 30 to loosen the pivot F and slide back the outer member M, after the operation above described for fracturing the cast along the line of the partial ridge here shown is carried out.

35 It will be understood that the construction and operation of both upper and lower trays is the same, except that the palatal arch N (Fig. 5) of the upper tray here shown in cross section is dispensed with in 40 the lower tray shown in Fig. 4, in which, of course, there is provided a lingual opening O.

It will be understood that various changes and modifications may be made in the constructions shown while still retaining the invention defined by the claims.

What I claim is:

1. A dental impression tray for full upper and lower jaws, comprising inner and 50 outer tray members, a handle, a ridge in said tray conforming in shape to the line of separation of said inner and outer tray members for predisposing moulding material after it hardens in said tray to breakage 55 along said line, and means co-operating with said handle and said tray members for positively and rigidly holding the same in as-

sembled position and permit movement of the tray members with respect to each other.

2. A dental impression tray for full upper and lower jaws, comprising outer tray members and an inner tray member, a handle, a ridge in said tray conforming in shape to the line of separation of said inner and outer tray members for predisposing moulding material after it hardens in said tray to breakage along said line, a threaded pivot 60 co-operating with said handle and said tray members for positively and rigidly holding the latter in assembled position and to permit separation of the outer tray members without disconnecting said members from the tray.

3. A dental impression tray, comprising outer members, an inner member, a handle, a pivot on said handle, a wedge arranged to cooperate with said handle and the inner tray member to hold said member in position with respect to the outer tray members, an upturned rim on the outer edge of the inner tray member, and an upturned rim on the inner edge of each of said outer tray members, said rims being arranged to abut and form a ridge within the tray trough of a shape approximating that of a set of teeth.

4. A dental impression tray, comprising outer members, an inner tray member, a handle, a wedge arranged to cooperate with said inner tray member to hold the same in position, a pivot on said handle to which the outer tray members are attached, an upturned rim on the outer edge of the inner tray member, and an upturned rim on the inner edge of said outer tray members, said rims being arranged to abut and form a ridge within the tray trough of a shape approximating that of a set of teeth.

5. A dental impression tray, comprising outer tray members, an inner tray member, a handle, a wedge cooperating with said inner tray member for holding the same in position, a removable pivot on said handle to which said outer tray members are attached, an upturned rim on the inner edge of each of the outer tray members, and an upturned rim on the outer edge of said inner tray member, said rims being arranged to abut and form a ridge within the tray trough, whereby plaster which has hardened in said tray will be predisposed to breakage along the line of said ridge.

In testimony whereof, I have hereunto set my hand.

LOUIS BALTER.
